United States Patent Office.

L. A. CHICHESTER, OF POUGHKEEPSIE, NEW YORK.

Letters Patent No. 95,768, dated October 12, 1869.

IMPROVED CRIB OR CRADLE.

The Schedule referred to in these Letters Patent and making part of the same.

To all whom it may concern:

Be it known that I, L. A. CHICHESTER, of Poughkeepsie, in the county of Dutchess, and State of New York, have invented a new and useful Improvement in Cribs and Cradles; and I do hereby declare that the following is a full, clear, and exact description thereof, which will enable others skilled in the art to make and use the same, reference being had to the accompanying drawings, forming part of this specification.

My invention relates to cradles, and consists in forming each end of the same of a single piece of wood, which is extended high above the body, so as to form a convenient and suitable support for mosquito-nets, blankets, &c.

In the drawings is represented a cradle provided with end-pieces according to my improvement. Said ends A are formed of a single piece of wood, of proper shape and size. The extreme ends of the bows have rockers attached, and they extend an equal, but considerable distance above the body of the cradle. The cradles heretofore manufactured have been provided with but one end-piece which extends above the body, and hence, no means have been provided which have a permanent connection with, or form part of the cradles, for properly supporting blankets, nets, or other similar articles with which it is often necessary to cover the cradle, to protect the child lying therein from a draught of air, from too bright light, or from insects, &c. It is highly important that a large space

should be formed beneath a blanket, so that the supply of fresh air for the child may not soon become exhausted.

It is also desirable that the blanket or net should be supported from the floor evenly at its four corners, and not liable to be reached by the arms or feet of the child when tossing about during sleep, or while awake, thus rendering the care of an attendant less frequently necessary to readjust the canopy.

I purpose forming the connection between the two end-pieces A A by means of bars E. The legs are also connected by cross-bars, C, and the spaces thus formed are filled with slats of ornamental design.

Having thus described my invention, What I claim as new, and desire to secure by Letters Patent, is—

A cradle composed of the body formed of the bars E and slats F, provided with the end-pieces A A, extended above the body, as shown, and each formed of one piece of bent wood, having rockers B attached, and provided with the cross-bars C and slats D, as set forth for the purpose specified.

The above specification of my invention signed by me, this 3d day of June, 1869.

L. A. CHICHESTER.
